US0D1073897S

(12) **United States Design Patent** (10) **Patent No.:** **US D1,073,897 S**
(45) **Date of Patent:** **** May 6, 2025**

(54) **SKIN HUMIDIFIER**

(71) Applicant: **AISIN CORPORATION**, Kariya (JP)

(72) Inventors: **Takumi Masuda**, Kariya (JP); **Akira Saitou**, Kariya (JP)

(73) Assignee: **AISIN CORPORATION**, Kariya (JP)

(**) Term: **15 Years**

(21) Appl. No.: **29/866,457**

(22) Filed: **Sep. 13, 2022**

(30) **Foreign Application Priority Data**

Jun. 6, 2022 (JP) ..... 2022-012059 D

(51) **LOC (15) Cl.** **23-04**

(52) **U.S. Cl.**

USPC **D23/356**

(58) **Field of Classification Search**

USPC D23/356, 359, 360, 364, 333, 332, 354

CPC F24F 2006/008; F24F 6/00; F24F 6/10;
F24F 2221/12

(57) **CLAIM**

The ornamental design for a skin humidifier, as shown and described.

DESCRIPTION

FIG. 1 is a rear perspective view of a skin humidifier showing our new design;

FIG. 2 is a rear view thereof;

FIG. 3 is a top plan view thereof;

FIG. 4 is a right side view thereof;

FIG. 5 is a left side view thereof;

FIG. 6 is a perspective view showing a louver of the skin humidifier for clear and complete disclosure thereof; and, FIG. 7 is a rear view showing a louver of the skin humidifier for clear and complete disclosure thereof.

The broken lines illustrate portions of the skin humidifier that form no part of the claimed design.

1 Claim, 7 Drawing Sheets
